CARRYING CASE FOR A FISHING ROD AND REEL

Albert G. Heidtman and Albert H. Tietjen, both of 515 Colonial Way, Reno, Nev. 89502

Filed Aug. 27, 1969, Ser. No. 18,862

Term of patent 14 years

Int. Cl. D3—99

U.S. Cl. D87—1

FIG. 1 is a front perspective view of a carrying case for a fishing rod and reel embodying our new design;

FIG. 2 is a top plan view thereof;

FIG. 3 is a bottom plan view thereof;

FIG. 4 is a rear elevational view thereof;

FIG. 5 is an end view as seen from the left hand end thereof;

FIG. 6 is an end view as seen from the right hand end thereof; and

FIG. 7 is a transverse sectional view thereof taken along the line 7—7 of FIG. 2.

We claim:

The ornamental design for a carrying case for a fishing rod and reel, as shown.
